UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

CAR-BOLSTER.

No. 825,083.

Specification of Letters Patent.

Patented July 3, 1906.

Application filed August 23, 1905. Serial No. 275,384.

To all whom it may concern:

Be it known that I, ETHAN I. DODDS, a citizen of the United States, residing at Pullman, in the county of Cook and State of Illinois, have invented certain new and useful Improvements in Car-Bolsters, of which the following is a specification.

My invention concerns metallic car-bolsters, and involves the use of angle-bars riveted to the sides of the bolster, the top plate thereof being secured to said angle-bars.

By employing bars of different sizes and weights the construction and strength of the bolsters may be varied and made to conform to the strains to which it may be subjected. By this means a standard size of bolster may be varied to meet the demands of the particular type of car it is to be employed in. The depth of the sides of the bolster may also be changed somewhat by modifying the position of the angle-bars relative to the sides.

In the accompanying drawings I have illustrated an embodiment of my invention, wherein—

Figure 1 is a perspective view of a truck-bolster embodying my invention. Fig. 2 is a central vertical longitudinal section of both a body and truck bolster constructed according to my invention. Fig. 3 is an enlarged end view of the two bolsters shown in Fig. 2. Fig. 4 is an enlarged section of both bolsters on the line 4-4 of Fig. 2 as viewed in the direction indicated by the arrows. Fig. 5 is the blank from which the body-bolster is made, and Fig. 6 is a similar blank from which the truck-bolster is made.

The description of the manufacture of the body-bolster from the blank shown in Fig. 5 will suffice to show how the truck-bolster is made from its blank, since the operations are identical, the truck-bolster differing from the body-bolster only in respect to size as far as the main portion of the bolster is concerned.

To make the body-bolster I press out of the plane of a rectangular sheet of metal 10 four tapering ribs 11 by bending the metal upwardly on the lines 12, which extend inwardly from each end of the sheet a portion of their length parallel and which then converge and meet at the points 13. This stamping operation gives the outer longitudinal portions of the sheet which are to comprise the sides of the bolster in its finished

form their bellied shape. Sides 14 are then bent upwardly on the parallel lines 15, so as to be at right angles with the central portion of the bottom 16. The central strip of the sheet is bent on lines 17 and 18, so as to form intermediate inclined and horizontal end portions of the bottom. These bending operations are preferably performed by submitting the sheet to the action of properly-shaped dies, the operations being performed simultaneously. By this manipulation of the sheet I produce the main portion of the bolster, and it will be noted that the sides are bellied, the surplus metal at their ends being taken up in the inturned tapering ribs 11, and that the bottom, comprising the central portion 16, the inclined portions 19, and the end horizontal portions 20, is integral with the sides.

As stated above, the main portion of the truck-bolster is made from the blank illustrated in Fig. 6 in a similar manner. To the upper edges of the body-bolster I rivet angle-bars 21 adjacent to their upper edges and with the flanges of the angle-bars extended outwardly. If desired, the tapering ribs may be supplied with fillets 22 to facilitate the riveting of the angle-bars to the sides. Tension-plate 23 is riveted to the flanges of these angle-bars. Dish-shaped spacing members 24 are riveted to the sides of the bolster to space them apart and at the same time to join them together, the sides of the spacing members being recessed to conform to the surfaces of the inwardly-pressed ribs.

The truck-bolster is similar to the body-bolster; but its top angle-bars 25 extend over only a portion of its length, as shown in Fig. 2, its top compression-plate 26 being riveted to said angle-bars, as shown most clearly in Figs. 1 and 3. In the truck-bolster two spacing members 27 are employed at each end, and the rivets which hold them in place pass also through the side guides 28. It will be apparent that the strength of these bolsters may be varied to some extent by using angle-bars of different strengths and weights, and it will also be obvious that the depth of the sides may be varied by riveting the angle-bars to the sides with their flanges a distance above the upper edges of the sides.

My invention is not limited to the details of construction as shown and described above

except in so far as they are made the subject-matter of specific claims.

This patent is intended to embrace only so much of the disclosure made herein as is covered by the claims.

I claim—

1. A car-bolster having side plates, each with an integral rib pressed out of the plane thereof at each end, a bottom plate, and angle-bars riveted to said side plates adjacent to their upper edges, substantially as described.

2. A car-bolster having side plates, each with an integral rib pressed out of the plane thereof at each end, a bottom plate, angle-bars riveted to said side plates adjacent to their upper edges, and a top plate riveted to said angle-bars, substantially as described.

3. A car-bolster having side plates, each with an integral rib pressed out of the plane thereof at each end, a bottom plate, and angle-bars with outwardly-extended flanges riveted to said side plates adjacent to their upper edges, substantially as described.

4. A car-bolster having side plates, each with an integral rib pressed out of the plane thereof at each end, a bottom plate, angle-bars with outwardly-extended flanges riveted to said side plates adjacent to their upper edges, and a top plate riveted to said outwardly-extended flanges, substantially as described.

5. A car-bolster having side plates, each with an integral rib pressed out of the plane thereof at each end, a bottom plate integral with said side plates, and angle-bars secured to said side plates adjacent to their upper edges, substantially as described.

6. A car-bolster having side plates, each with an integral rib pressed out of the plane thereof at each end, a bottom plate integral with said side plates, angle-bars riveted to said side plates adjacent to their upper edges, and a top plate riveted to said angle-bars, substantially as described.

45 7. A car-bolster having bellied side plates, each with an integral tapered rib pressed out of the plane thereof at each end, a bottom plate, and angle-bars riveted to said side

plates adjacent to their upper edges, substantially as described.

50

8. A car-bolster having bellied side plates, each with an integral tapered rib pressed out of the plane thereof at each end, a bottom plate, angle-bars riveted to said side plates adjacent to their upper edges, and a top plate 55 riveted to said angle-bars, substantially as described.

9. A car-bolster having bellied side plates, each with an integral tapered rib pressed out of the plane thereof at each end, a bottom plate 60 integral with said side plates, and angle-bars with outwardly-extended flanges riveted to said side plates adjacent to their upper edges, substantially as described.

10. A car-bolster having bellied side plates, 65 each with an integral tapered rib pressed out of the plane thereof at each end, a bottom plate integral with said side plates, angle-bars with outwardly-extended flanges riveted to said side plates adjacent to their upper edges, 70 and a top plate riveted to the outwardly-extended flanges of said angle-bars, substantially as described.

11. A car-bolster having bellied side plates, 75 each with an integral tapered rib pressed inwardly out of the plane thereof at each end, a bottom plate integral with said side plates for substantially its entire length, and angle-bars with outwardly-extended flanges riveted to the outer sides of said side plates, substantially as described.

12. A car-bolster having bellied side plates, 80 each with an integral tapered rib pressed inwardly out of the plane thereof at each end, a bottom plate integral with said side plates 85 for substantially its entire length, angle-bars with outwardly-extended flanges riveted to the outer sides of said side plates, and a top plate riveted to the outwardly-extended flanges of said angle-bars, substantially as de- 90 scribed.

ETHAN I. DODDS.
